UNITED STATES PATENT OFFICE.

WILLIAM H. GRINDLEY, OF COUGLETON, ENGLAND, ASSIGNOR TO WILLIAM S. PITCAIRN, OF NEW YORK, N. Y.

DESIGN FOR A DISH.

SPECIFICATION forming part of Design No. 33,280, dated October 2, 1900.

Application filed September 8, 1900. Serial No. 29,461. Term of patent 34 years.

To all whom it may concern:

Be it known that I, WILLIAM H. GRINDLEY, a subject of the Queen of Great Britain, residing at Cougleton, county of Chester, England, have invented a new and original Design for a Dish; and I do declare the following to be a full, clear, and exact description of the same, reference being had to the accompanying drawings, forming part hereof.

10 In the drawings, Figure 1 is a plan view, and Fig. 2 is a vertical central section and partial side elevation, of a dish embodying my design.

The leading features of my design are as follows: The rim of the dish is a smooth continuous curve. Within the rim and parallel thereto is arranged a series of embossed ornamentalations consisting of a smooth curve *a*, terminating in an inwardly-curved bead or 15 circle *b* at each end alternating with a conventional trifoliate figure *c*, pointing inward. The center of the dish is depressed, the de-

pression being bounded by a continuous curve, which is provided with an embossed ornamentation consisting of short radial lines *d*. 25 Between the center of the dish and its outer edge there is a row of embossed ornamentations consisting of a trifoliate figure *e* and a quadrifoliate figure *f*, alternately arranged between each pair of such figures there being placed a conventionalized stalk *g*, provided with flowers *h*, the top of the same in each case being toward the figure *f* and away from the figure *e*.

What I claim is—

35 The design for a dish substantially as shown and described.

In testimony whereof I have signed this specification, this 21st day of August, 1900, in the presence of two witnesses.

WILLIAM H. GRINDLEY.

Witnesses:

JOHN H. COPESTAKE,
GEO. HOLMESTON.
